Des. 1429

James J. Morrisett, of New York, N.Y.
Assignor to Jacob L. Dodge, same place.
Whole No. 1429. Letters Patent No. 64, dated May 28, 1861.

The schedule referred to in these Letters Patent and making part of the same.

To all whom it may concern:

Be it known that I, James J. Morrisett, of New York City, in the County and State of New York, have invented a new Design for Hats, and I do hereby declare that the following is a full, clear and exact description of the same, reference being had to the accompanying drawings forming part of this specification in which -

Figure 1. is a front view of a hat of my new design.

Figure 2. is a side view of the same.

Figure 3. is a central section of the same from back to front.

Figure 4. is a transverse section of the same.

Similar letters of reference indicate corresponding parts in the several figures.

My design consists in a novel configuration of the brim of a hat made of straw or other material.

Des. 1429

A is the brim rolling all round the crown *B*, and having both its upper and lower edges united therewith as shown in Figures 3 and 4, the lower edge meeting the lower edge of the crown, and its upper edge meeting the crown about half way up the latter. The profile of the brim is curved both from front to back and transversely, the curvature being downward from the sides toward the front and back, as shown in Figures 2 and 3, and upward from front & back toward each side, as shown in Figures 1 and 4. The transversesectional form of the brim at each side is nearly that of a circle with a segment cut off the chord being formed by the side of the crown, as shown in Figure 4, and at the front and back it is that of an ellipse with a segment cut off by a chord slightly oblique to its minor axis, the chord being formed by the front or back of the brim; and between the front or back and sides, the form gradually assumes the one or the other of the above described forms as it approaches the sides or the front or back.

What I claim as my design and desire to secure by Letters Patent is
The configuration of the brim of the hat as illustrated by the several
Figures of the drawing and herein described.
